tion of Wisconsin

Application November 9, 1940, Serial No. 96,447

Term of patent 7 years

To all whom it may concern:

Be it known that I, Clement J. Thelander, a citizen of the United States, residing at Chicago, in the county of Cook and State of Illinois, have invented a new, original, and ornamental Design for a Golf Club Head Cover, of which the following is a specification, reference being had to the accompanying drawing, forming a part thereof.

The single figure of the drawing is a perspective view of one side of a golf club head cover embodying my design, a view of the other side

being substantially the same but without the flag insignia.

The characteristic feature of my design resides in the combination on a golf club head cover of the specific configuration disclosed, of a contrastingly colored flag member, applied to one side or face thereof, all as shown.

I claim:

The ornamental design for a golf club head cover, substantially as shown and described.

CLEMENT J. THELANDER.
